UNITED STATES PATENT OFFICE.

ARTHUR A. AUST, OF COLUMBUS, OHIO.

WINDMILL.

Application filed January 25, 1924. Serial No. 688,572.

To all whom it may concern:

Be it known that I, ARTHUR A. AUST, a citizen of the United States, residing at Columbus, in the county of Franklin and State of Ohio, have invented certain new and useful Improvements in Windmills, of which the following is a specification.

The present invention is directed to improvements in wind mills.

10 The primary object of the invention is to provide a wind mill so constructed that the vanes thereof will be disposed vertically and so mounted that the position thereof will be automatically shifted when the wind reaches 15 an abnormal velocity, thereby eliminating the possibility of injury to the apparatus.

A further object of the invention is to provide means whereby the frame supporting the vanes will be permitted to travel in 20 a circle so as to assure that the vanes will be successively positioned to be effectively acted upon by the wind.

With these and other objects in view, as will appear as the description proceeds, the 25 invention consists in the novel features of construction, combinations of elements and arrangements of parts, and hereinafter to be fully described and pointed out in the appended claims.

30 In the accompanying drawing:

Figure 1 is a front elevation of the device,

Figure 2 is a vertical sectional view through the two wind mill units,

Figure 3 is a top plan view,

35 Figure 4 is a detail sectional view through the gearing of one of the units,

Figure 5 is a detail sectional view of the governor actuated mechanism,

40 Figure 6 is a transverse sectional view through one of the vanes,

Figure 7 is a sectional view on line 7—7 of Figure 2, and

Figure 8 is a horizontal sectional view through a modified form of the invention.

45 Referring to the drawings 1 designates a foundation, preferably cement and upon which is suitably mounted a circular track 2. Fixed centrally in the foundation is a vertical anchor shaft 3 to which is pivotally connected one corner of the substantially triangular shaped frame 4 which has the same shape as the supplemental frame 5, the latter being comparatively small and spaced vertically from the former. These frames 50 are braced by connecting bars 6 and 7 or in any other desired manner. The frame 4 is

provided with suitable bearings 8 for supporting the horizontal driving shaft 9, the purpose of which will appear later.

A pair of wind mill units 10 are employed 60 and comprise a gear wheel 11 which has its hub 12 loosely engaged with the vertical main shaft 13, the upper end of which is journaled in the frame 5 while the lower end of said shaft is journaled in a bearing 14 65 of the frame 4.

Upper and lower spider frames 15 are included in each unit 10, said frames having their rims 16 preferably hexagonal in contour and have their hubs 17 fixed to the shaft 70 13. Each rim 16 is provided with equally spaced bearings 18, six in number, a bearing being located at each point of angularity of the respective rims. The vertically disposed vanes 19 are preferably of the 75 shape shown in Figure 6 of the drawings and may be formed of any suitable material, and associated with each vane is a tube 20, the ends of which extend for a short distance beyond the respective ends of said 80 vanes. The upper extended ends of the tubes 20 are journaled in the bearings 18 of the rim of the upper frame 15 while the lower ends thereof have slidably and rotatably engaged therein stub shafts 21 which engage the bearing 18 of the lower frame 15, there being gears 22 fixed to the lower ends of said stub shafts which mesh with the gear wheel 11. The stub shafts 21 are provided with pins 23 adapted to ride in the 90 obliquely disposed slots 24 formed in the lower ends of said tubes, the purpose of which will later appear.

The hub 12 of the gear wheel 11 has fixed thereto a gear 25 which meshes with the gear 95 26 fixed to the upper end of the shaft 27 journaled in the frame 4, there being a gear 28 fixed to the lower end of said shaft. The gears 28 mesh with gears 29 fixed to the lower ends of the shafts 13 and also fixed 100 to said shafts are beveled gears 30. The gears 30 mesh with similar gears 31 fixed to the ends of the transverse shaft 32 which is journaled in bearings 33 carried by the frame 4. Fixed centrally to the shaft 32 is 105 a beveled gear 34 which meshes with a similar gear 35 fixed to the adjacent end of the shaft 9, the other end of said shaft having a beveled gear 36 fixed thereon which meshes with a similar gear 37 which has associated 110 therewith a beveled gear 38. The gear 38 meshes with a beveled gear 39 upon the ad-

jacent end of the driven or power shaft 40 which may be coupled in any suitable manner to the device to be operated, such for instance as a pump.

5 It is desired to adjust the vanes 19 to positions to offer as little resistance to the wind as possible should the velocity thereof obtain abnormal proportions and in order to accomplish this a centrifugal governor 41 of 10 any well known type is employed, said governor being suitably mounted on a cross bar 42, carried on the frame 4, said governor having its shaft 43 provided with a beveled gear 44 which meshes with a similar gear 45 fixed to the shaft 9. This governor controls the operation of the rod 46 which has its upper end pivotally connected with the inner end of a lever 47, said lever being pivotally connected intermediate its ends to a bracket 20 48 carried by the frame 5. To simultaneously lift the vanes 19 each unit 10 has associated therewith substantially annular frames 49 which include spokes and a central hub 50 slideable on the shafts 13, said hubs having 25 swivelly connected thereto the ends of the cross bar 51, said cross bar being pivotally connected with the lever 47 through the medium of the yoke 52.

It will be apparent that as the wind passes 30 between and through the units 10 that the vanes 19 will be successively positioned to be acted upon thereby, owing to the fact that as the units rotate said vanes will be positively positioned for action upon by the 35 wind by the gears 22 and 11. When the velocity of the wind becomes abnormal and the shafts 32 and 9 rotate at such speed as to cause the governor 41 to operate to elevate the cross bar 51 and thus the tubes 20, which 40 support the vanes 19. Owing to the presence of the pins 23 and slots 24 the tubes will be given a partial rotation so as to bring the respective vanes with their edges into the wind, thereby reducing the speed of the 45 units to prevent injury to the apparatus. It will be of course obvious that these tubes can be elevated manually upon pulling

downwardly upon the rod 46 and anchoring the same, whereby the speed of the apparatus may be readily controlled and regulated.

In the modified form of the invention as shown in Figure 8, in lieu of the gears 22 and gear 11 sprockets 53 are employed and have trained therearound a sprocket chain 55. This sprocket chain is also trained around a sprocket 55 which is fixed with a gear 56, said gear being in mesh with a gear 57 suitably fixed upon the lower frame 4.

What is claimed is:

1. A wind motor comprising a vertical support, a pair of upper and lower radial frames connected with said support and rotatable in a horizontal plane axially with respect thereto, and a pair of wind mill units including vertically disposed vanes mounted for rotation about vertical axes and positioned between said frames.

2. In a wind motor, a vertical support, horizontally disposed vertically spaced frames extending radially from said support, an arcuate trackway for supporting said frames and to permit of their axial adjustment relative to said support, a pair of wind mill units mounted for rotation about vertical axes carried by the outer ends of said frames, each of said units consisting of a plurality of vertically disposed vanes, and motion transmitting appliances connected with said vanes.

3. In a wind mill, an arcuately adjustable supporting frame, supplemental frames carried in connection with said first-named frame, vanes carried by said supplemental frames and rotatable about vertical axes, a driven member, motion transmitting appliances between said vanes and said driven member, and a governor mechanism operable automatically to adjust the working positions of said vanes in accordance with predetermined wind velocities.

In testimony whereof I affix my signature,

ARTHUR A. AUST.
